UNITED STATES PATENT OFFICE

115,508

DESIGN FOR A BICYCLE LAMP OR SIMILAR ARTICLE

Bernard J. Perry and Ralph P. Nomsen,
Sioux City, Iowa

Application April 10, 1939, Serial No. 84,179

Term of patent 14 years

To all whom it may concern:

Be it known that we, Bernard J. Perry and Ralph P. Nomsen, citizens of the United States of America, residing at Sioux City, county of Woodbury and State of Iowa, have invented a new, original, and ornamental Design for a Bicycle Lamp or Similar Article, of which the following is a specification, reference being had to the accompanying drawing, forming a part thereof, wherein:

We claim:

The ornamental design for a bicycle lamp or similar article, as shown.

BERNARD J. PERRY.
RALPH P. NOMSEN.
